CLAIM

The ornamental design for the set of disposable razors, as shown and described.

DESCRIPTION

FIG. 1 is a front side view of showing my new design of the set of disposable razors.

FIG. 2 is a front view thereof.

FIG. 3 is a back view thereof.

FIG. 4 is a front end view thereof.

FIG. 5 is a back end view thereof; and,

FIG. 6 is side views of any one of the razors from the set of disposable razors.

The broken lines in the drawings are for the purpose of illustrating environmental structure which form no part of the claimed design.

1 Claim, 6 Drawing Sheets
